(57) **CLAIM**

The ornamental design for a control knob for a shock absorber, as shown and described.

DESCRIPTION

FIG. 1 is a front, right side, bottom perspective view of a control knob for a shock absorber showing my new design; FIG. 2 is a rear, left side, bottom perspective view thereof; FIG. 3 is a front view thereof;

FIG. 4 is a rear view thereof;

FIG. 5 is a left side view thereof, a right side view being symmetrical;

FIG. 6 is a top plan view thereof; and,

FIG. 7 is a bottom plan view thereof.

The broken lines in the Figures show portions of the control knob that form no part of the claimed design.

The control knob can be for a shock absorber for a motorcycle. The control knob can be for adjusting a buffering property, a vibration suppression characteristic, and a function of a motorcycle body posture control for a motorcycle.
